6 Claims. (Cl. 24—205)

This invention relates to separable fasteners which can be made of metallic or non-metallic materials.

It is an object of the invention to provide a separable fastener having fastener elements capable of being attached directly to the article which is to be provided with the fastener, without first clamping the elements to the usual fabric tapes by means of which the fastener stringers are formed.

According to the invention the fastener elements are provided with at least one connecting stud forming an extension of the element and by means of which the element is directly attached to the article to be provided with the separable fastener. In order to enable the connection of the fastener elements to the article in correct and simple manner the elements are first strung on a carrier consisting of rigid material but which owing to its shape or feeble cross sectional area is rendered flexible, so as to obtain fastener stringers having the required flexibility for the operation of the usual slider producing engagement and disengagement of the cooperating elements. The carrier can preferably consist of a thermoplastic material, such as high molecular condensation products, polyamides and the like, in the shape of threads, wires or bands, on which the fastener elements are longitudinally spaced. Such carrier threads can be obtained by drawing the material nearly to its limit of expansion, so that the threads do not expand any more and the fastener elements fixed thereon always keep their correct spacing, while in transverse direction these threads are extremely flexible to allow an easy displacement of the slider along the stringers.

A certain number of embodiments of separable fasteners according to the invention are illustrated by way of example in the accompanying drawings, in which

Fig. 115 is a plan view of a fastener element.

Fig. 116 is a plan view of the fastener element of Fig. 115 after attachment to the fabric.

Fig. 1 shows a portion of a separable fastener according to the invention having fastener elements which are directly attached to the edge portions along an opening of an article, for example of a piece of clothing which is to be provided with the fastener. Fig. 2 shows a portion of the fastener stringer of this fastener. The fastener elements 1 are provided at one end with the usual coupling projection 2 and the socket 3. At the end of the fastener elements opposed to that by which they engage one another each element is provided with a connecting stud 4 which serves for directly attaching the fastener element to the edge portion of a piece of clothing or any other article 5 from fabric, leather etc. The cross sectional area of the connecting stud 4 is smaller than that of the fastener element 1 so that a shoulder 6 is formed between the element and the connecting stud, which shoulder serves to guide the usual slider 7 provided with a pull tab 8. The various fastener elements are spaced longitudinally on a carrier 9 of thread or wire shape. The material of this carrier is flexible but not expansible. For example the carrier can be formed from a thread or polyamide; also other synthetic products of the group of high molecular polycondensation products or other thermoplastic materials can be used. For example, the fastener elements are directly die-cast on the carrier or pressed upon the latter. They can consist of metal or of thermoplastic material, for example of the same material as the carrier 9. The flexible fastener stringer thus formed by the carrier and by the fastener elements fixed thereon is attached to the article 5 by means of the connecting studs 4 of the fastener elements. As shown, the stringer is placed with the connecting studs upon the edge portion of the article and then sewing stitches 10 are passed over the studs to fix them to the article. The studs 4 are provided with an enlargement or head 11 at their ends, so that they can not be pulled out of the stitches 10. The resiliently flexible carrier 9 maintains the fastener elements at their correct mutual distance and the stringer is flexible in its longitudinal plane so that an easy engagement and disengagement of the cooperating elements and a smooth run of the slider is obtained.

In the example according to Figs. 3 and 4 the connecting studs 4 of the fastener elements 1 have a roof-shaped cross section. For sewing the stringer to the cloth 5 the stringer is placed on the cloth with the base of the connecting studs on the surface of the cloth and then the

studs are attached to the cloth by means of a sewing machine, the stitches passing between the enlargements 11 and 12 of the studs. When the sewing needle arrives on top of a connecting stud it can slide downwardly the inclined surfaces 13 of the stud and does not brake.

In the example according to Figs. 5 and 6 the carrier of the fastener elements is formed by two threads 14 and 15 of synthetic material on which the fastener elements are die-cast. This modification is advantageous for greater models of fasteners. The thread 14 is of circular cross section and the thread 15 of oval cross section; obviously the cross sectional area of these threads can have any other shape.

In the example according to Fig. 7 the connecting studs 4 are longer than those shown in the previous examples. Besides the carrier thread 9 traversing the fastener elements 1, the connecting studs 4 are also traversed by parallel threads 16 and 17. All threads are flexible so as to impart the required flexibility to the stringer.

According to Fig. 8 the connecting stud of the fastener elements 1 is composed of a wider portion 18 situated adjacent the fastener element 1 and of a narrower end portion 19. The wider portion 18 is traversed by two carrier threads 20, while the narrower portion 19 of the studs serves to attach the stringer to the article by means of stitches passing over this portion.

In Figs. 9 and 10 the thread or wire 21 forming the carrier of the fastener elements is undulated. This thread can be formed from a high molecular polycondensation product or from a steel wire.

According to Fig. 11 the carrier of the fastener elements 1 is formed by curved webs 22 which are die-cast in one piece with the fastener elements 1 and the connecting studs 4.

In the example according to Fig. 12 the flexible carrier 23 of the fastener elements 1 is formed as strip and traverses the wider portion 18 of the connecting studs.

In Fig. 13 the fastener elements 1 and the wider portions 18 of the connecting studs are die-cast on an undulated wire 24 and on a thread 9. Both threads or wires 9 and 24 can consist of polyamide or the thread 24 can also consist of steel.

In Fig. 14 the carrier of the fastener elements 1 is formed by two curved webs 25 extending between the wider portions 18 of the connecting studs. The complete stringer formed by the fastener elements, the connecting studs and the webs is cast in a single piece.

In the example according to Figs. 15 and 16 the carrier of the fastener elements 1 is formed by two parallel webs 26 which are cast in a single piece with the wider portion 18 of the connecting studs of the fastener elements. The fastener elements could also be die-cast on a band-shaped carrier in which flexible webs 26 are formed by providing recesses 27. Instead of disposing the carrier 26 between the connecting studs as represented, the carrier could also be arranged between successive fastener elements 1.

In the example according to Figs. 17 and 18 the fastener element 1 is provided at one side with a groove 28 into which the carrier thread 9 can be inserted. Laterally of the groove 28 the material of the fastener elements forms projections 29 which, after insertion of the thread into the groove, are bent or pressed inwardly in order to close the groove and to press the fastener element firmly on the thread. The groove 28 could also be provided on the connecting stud 4. The fas-

tener element with the connecting stud in this example can be cast or punched out from sheet material. If desired, in the example according to Figs. 9, 10 and 13, the undulated thread or wire 21 or 24 could also be inserted in a corresponding groove in the fastener element or in the connecting stud. In this case the undulated or zigzag-shaped carrier and the fastener elements can be produced independently one from the other, and the carrier can be subsequently inserted into the groove of the elements while in the other case the fastener elements must be die-cast on the carrier.

In the example according to Fig. 19 the fastener elements 1 are fixed to a carrier 9 and a further thread 30 traverses the enlarged rear end of the connecting studs 4. The fastener elements and connecting studs are either die-cast on the threads 9 and 30, or the threads are subsequently inserted through corresponding holes in these portions.

In Fig. 20 the rear end of the connecting studs 4 are connected to each other by webs 31 cast in one piece with the fastener elements, and the wider portions 18 of the connecting studs are traversed by a band-shaped carrier 32.

In Fig. 21 the rear ends of the connecting studs 4 are connected by webs 31 and the thicker portions 18 of the connecting studs are connected by curved webs 32. The fastener elements 1, the connecting studs 4 and the webs 31 and 32 are cast in a single piece. One or both webs 31 and 32 could also be formed by threads or strips inserted through openings or grooves of any desired cross section provided in the connecting studs.

In the examples according to Figs. 22 to 28 the fastener element 1 is provided with a central opening 33 which is obtained when producing the fastener elements by casting or by punching. On the level of the opening 33 opposite sides of the fastener element are provided with bulged portions 34. The fastener elements are threaded by means of their opening 33 to a string of polyamide or the like, and correctly spaced thereon and afterwards pressure is applied to the bulged portions of the elements so that the side faces of the elements become flat as shown in Fig. 24 and the thread 35 is fixed by pressure in the opening 33. In order to attach the stringer to a piece of clothing or any other article the connecting studs 4 are sewn to the article. In order to prevent a sliding movement of the attached fastener elements the connecting studs 4 are formed with enlargements 36 or 37 between which the sewing stitches pass above the studs. In Figs. 27 and 28 the connecting stud is formed with a wider portion 18 and with a narrower portion 19 having a head 38 at its end.

Figs. 29 to 33 show fastener elements provided with connecting studs according to the invention and which are obtained by punching the elements out of sheet material. According to Fig. 29 the connecting studs 4 are disposed according to the median axis of the fastener elements 1, while according to Fig. 30 the connecting studs 4 are disposed laterally on the fastener elements 1. According to Fig. 32 the fastener elements are punched out from a strip of sheet material in such manner that one fastener element 1' belongs to one stringer of a cooperating pair of separable fastener stringers while the next following fastener element 1'' belongs to the second stringer of the pair. The openings 33 for the insertion of the carrier thread are punched out simultaneously with the fastener elements. Fig. 33 shows the fastener element fixed on the carrier thread

35 by means of pressure applied to opposed sides of the element at the height of the carrier.

Figs. 34 to 39 show particular constructions of connecting studs for the fastener elements. The connecting stud 4 is of triangular cross section, one face 39 of the stud extending at right angles to the piece of cloth to which the stud is to be fixed, while the face 40 is inclined relatively to the surface of the cloth. In the example according to Figs. 34 to 36 the studs 4 are provided on the side of the inclined surface 40 with two spaced enlargements 41 between which can pass the sewing stitches for attaching the fastener element to an article. The upper side of the enlargements 41 is provided with a plane face 42 extending flush with the upper edge of the connecting stud and serving to guide the pressure foot of the sewing machine which is used to sew the connecting studs to an article 5.

20 In the example according to Figs. 37 and 38 the enlargements 43 project laterally from the inclined surface 40 and form again an upper plane face 42.

According to Fig. 39 the enlargements 44 project from the vertical face 39 of the studs and also form an upper plane face 44 flush with the upper edge of the stud.

According to Fig. 40 the connecting studs 4 of the fastener elements 1 are provided with indented edges 45. The indentations at opposite edges are longitudinally displaced one relatively to the other so that the cross sectional area of the stud does not become too weak. In Fig. 41 the opposite edges of the connecting stud 4 are undulated and in Fig. 42 the edges have zigzag-shape. As shown in Fig. 43 the upper side of the connecting studs 4 is formed with inclined surfaces 49 extending also over the enlarged end 46 of the studs. Instead of forming both longitudinal edges of the connecting studs as shown in Figs. 40 to 42, only one of the edges could be provided with teeth or indentations, while the other edge could be limited by a straight line.

45 In the example according to Figs. 44 to 47 the fastener elements 80 are provided with the usual coupling projection 81 and with the socket 82. The fastener elements are provided with a connecting stud 83 by means of which the elements are attached to a piece of clothing or other article 84. 85 represents the usual slider by means of which the cooperating stringers are engaged and disengaged.

55 The connecting studs 83 are provided with a portion 86 of reduced cross section so as to form a circular groove on the connecting studs, into which the band-shaped carrier of the elements is inserted. The carrier according to Fig. 47 is formed by two separate strips 87 and 88 which are provided with recesses 89 and 89' which, when the two strips are joined, form openings in the carrier to receive the reduced portions 86 of the connecting studs. The studs are engaged with their portions 86 into the recesses of one of the strips 87 or 88 before the two strips are joined and then the second strip is joined to the first one and the two strips are fixed together by means of an adhesive or by soldering or welding. The fastener elements 80 are thus firmly connected with the carrier and a stringer is formed which can be directly attached to a piece of cloth or leather etc. In the represented example the stringer is attached to the cloth by sewing, the stitches passing over a reduced portion of the connecting studs which are provided with a head 91 at their end so that they cannot be pulled out of the stitches.

The studs 83 are provided with a shoulder 92 against which abuts the edge of the article to which the stringer is attached.

The carrier 87, 88 is formed of rigid material of such cross sectional area that it is flexible in the plane of the stringer. The carrier can be made of thermoplastic material, particularly of high molecular condensation products, such as polyamide and the like. The fastener elements 80 can be made of metal, for instance of die-cast zinc or also of thermoplastic material.

In the modification according to Fig. 48 the carrier of the fastener elements is formed by a wider strip 93 and by narrower strip 94. The wider strip 93 is provided with recesses 95 into which the reduced portions 86 of the connecting studs are inserted. After insertion of these portions into the recesses 95, the narrower strip 94 is joined to the strip 93 and firmly connected with this strip so that the fastener elements are permanently secured to the carrier.

In the example according to Figs. 49 to 51 the fastener elements 80 are carried by a strip 96 which is provided with openings 97 through which the studs 98 are inserted.

As shown in Fig. 49 the studs 98 are inserted through the holes of the carrier and then a portion of the material of the studs is riveted at the rear side of the carrier. The studs could be secured to the carrier also by means of an adhesive or by soldering or welding. The fastener stringer can then be attached to the article 84 by sewing, of the connecting studs 98, the stitches passing over a portion 90 of reduced width.

In the example according to Figs. 52, 53 and 54 the fastener is formed by two stringers 101 connected to each other by the usual slider 103. Each stringer comprises fastener elements 104 provided with a coupling projection 105 and a socket 106. The fastener elements are longitudinally spaced on a flexible carrier 107 and each element 104 is provided with a connecting stud 108 having a pointed end 109. In proximity of the end of the stud this latter is pierced by an opening 110.

The fastener elements 104 can consist of metal or of thermoplastic material. The carrier 107 is formed by a thread or wire of any desired cross section. Preferably the carrier is formed by polyamide or any similar synthetic product. The carrier thread is inserted through corresponding openings in the fastener elements 104 and elements are fixed to the carrier by means of an adhesive or by pressure. Alternatively, the fastener elements can be directly cast on the thread 107.

For attaching the fastener stringers 101 to an article 111, for instance to a piece of cloth, the pointed end 109 of each connecting stud is stuck through the cloth in proximity of one edge thereof until the shoulders 114 of the connecting stud abut against a cloth and then a thread 112 is inserted through the holes 110 in the ends of the connecting studs projecting on the rear side of the cloth. At both ends of the stringer the thread 112 is fixed in any convenient manner to the cloth or to the stringer so as to lock the thread in the holes 110. The edge portion of the cloth is now folded down and by means of stitches 113 a seam is formed. The ends of the connecting studs are now locked in this seam and a firm and a reliable connecting of the fastener stringer with the article 111 is obtained. It is naturally also possible to attach the fastener stringer to an intermediary tape by sticking the ends 109 through the tape and locking them in the described manner on the

tape. Afterwards this tape can be sewn in ordinary manner to a piece of cloth.

The example according to Figs. 55 and 56 is similar to that represented in Figs. 52 to 54, only the shape of the connecting studs 108 is slightly modified.

In the example according to Figs. 57 and 58 the ends of the connecting studs 108 of the fastener elements 104 are slit so that tongues 115 are formed, which can be stuck through the cloth 111 for attaching the stringer to the cloth and afterwards these tongues can be bent down on the cloth so as to prevent removal of the studs from the cloth. In this case no locking thread 112 is required for attaching the stringer to the cloth.

In Fig. 59 the pointed end of the connecting stud 108 is bent at right angles and is stuck through a seam 117 of the cloth. The locking thread 112 is inserted through holes provided at a rear end of the connecting studs and prevents removal of the stringer from the seam 117.

In Fig. 60 the end portion of the connecting stud 108 of the fastener element 104 is provided with small prongs 118. This end portion is stuck through the edge of the cloth and after forming a seam 119 the small prongs 118 prevent the connecting studs from being pulled out of the seam. In Fig. 61 the connecting stud 118 is provided with hooks 120 which prevent the studs from being pulled out of the seam.

In the example according to Figs. 62 and 63 the originally pointed ends of the connecting studs 108 are stuck through the article 111 and then riveted at the rear side of the article, so that the material of the article is maintained between the rivet head 121 and the shoulder 114 on the connecting studs 108.

In Figs. 64 and 65 the pointed end of the connecting studs 108 is stuck through the cloth 111 and through a washer 122 and then riveted. Instead of a single washer for each connecting stud, a common washer strip 123 can be used for several or all connecting studs of a stringer. The connecting stud 108 is provided with a shoulder 114 bearing against the surface of the cloth 111 and with a shoulder 124 bearing against the washer 122.

While in the examples according to Figs. 52 to 65 the connecting studs 108 are situated in the plane of the stringer, Figs. 66 to 69 show a fastener element in which the connecting stud 125 extends transversely to the plane of stringer. The pointed end of the connecting stud is stuck through the edge portion of an article 111 and as shown in Fig. 66 a locking thread 112 is inserted through holes provided in the ends of the connecting studs. According to Fig. 67 the connecting stud is fixed to the cloth 111 by bending down the end 126 of the stud projecting at the rear side of the cloth. According to Figs. 68 and 69 the end of the connecting stud stuck through the cloth 111 is slit and forms two tongues 127 which can be bent down in opposite directions to attach the connecting stud to the cloth. The extension 128 of the fastener elements 104 serves to guide the slider.

In Figs. 70 and 71 the connecting studs 128 are inserted through openings 160 in the carrier 159 of a type shown in Fig. 51 and fixed by riveting at 161 to the carrier. For attaching the stringer to an article 111 the pointed end of the connecting stud is stuck through the article and locked at the rear side of the article by means of a thread 112 as previously described.

In the example according to Figs. 72 and 73 the

connecting studs 162 of the fastener elements 104 are provided with a portion 163 of reduced cross section which serves for securing the fastener elements to a carrier according to Figs. 47 or 48. This carrier is formed by two separate strips 87 and 88 forming between themselves openings to receive the reduced portion 163 of the connecting studs. As previously described, the connecting studs are placed in the recesses of one of the strips 87 or 88 and then the two strips are joined to each other and firmly connected by means of an adhesive or by soldering or welding. For attaching the stringer to an article 111 the pointed ends of the connecting studs 162 are stuck through the article and locked thereon by means of a thread 112 inserted through openings in the connecting studs.

In the example according to Figs. 74 to 75 a so-called covered fastener is represented in which the cloth 111 is used to hide the fastener members from view. For this purpose a fold 177 is formed in the cloth along an edge portion thereof and a connecting stud 178 provided laterally on the fastener members 104 is stuck through both branches of the fold 177. The end of the connecting stud projecting on the lower side of the fold is locked to the fold by means of a thread 112 inserted through an opening in the studs.

In the example according to Figs. 77 and 78 the carrier 184 is formed by a drawn thread of polyamide of rectangular cross section. The fastener elements 104 are made in a single piece with the connecting studs which form extensions of the fastener element. The studs are formed by a portion 179 of reduced cross section joining the fastener element, of a conical collar 180 followed by a reduced portion 181 and by an end cone 182 having a laterally projecting base 183. In order to attach the fastener elements 104 to the carrier, the studs are stuck through the carrier which may be provided with corresponding holes for this purpose. The material of the carrier is yieldable so that after passing the cone 182 and the collar 180 through openings of smaller diameter in the carrier, the material of the latter contracts about the reduced portion 179 of the studs and the fastener elements cannot be removed any more from the carrier 184, which is enclosed between the rear end face of the fastener elements 104 and the larger face of the frusto-conical collars 180. For attaching the so formed stringer to an article of cloth or other material, the cone-shaped ends 182 are stuck through the article 111 and if desired also through a washer strip 185 of polyamide or the like. A seam 119 can then be formed to enclose the cones 182, whereafter the studs are prevented from being pulled out of the article by the base 183 of the cones bearing against the washer strip 185.

In the example according to Figs. 79 and 80 the connecting studs of the fastener elements 104 are similar to those represented in Figs. 77 and 78, only the cone-shaped end 182 is replaced by a pointed hook-shaped end 186. The fastener elements 104 are fixed to the carrier 184 by sticking the studs through holes in the carrier 184 whereafter the conical collar 180 prevents a removal of the carrier, while attaching of the stringer to article 111 is obtained in the same manner as described with respect to Figs. 77 and 78.

In the modification according to Figs. 81 to 83 the connecting stud 187 has a hook-shaped pointed end forming a retaining surface 189 and a reduced portion 188. For attaching the fas-

tener elements 104 to the carrier 190 which is preferably formed by a thread of polyamide, the fastener elements are provided with an open slot 191 (Fig. 83) into which the carrier thread is inserted. After insertion of the thread, an extension 192 of the fastener element is bent down upon the thread as shown in Fig. 82, the thread being thus pressed together and the fastener element firmly seated thereon. The surface portion 193 of the fastener element serves as guide for the usual slider operating the stringers. In order to attach the stringer to a piece of cloth, the studs 187 are stuck through the cloth and through a washer strip 185 against which the retaining surface 189 is bearing to prevent removal of the stringer from the cloth 111.

In Figs. 84 to 86 the connecting stud 193 formed as extension of the fastener element 104 is stuck through the carrier 194 which penetrates into recesses 195 of the fastener element. The connecting stud is provided with a reduced portion 196 forming retaining surfaces 197 which bear against a washer strip 195 after the stud has been stuck through the cloth 111 and through the washer strip.

In the example according to Figs. 87 and 88 the carrier of the fastener elements 104 is formed by two distinct threads or wires 198 and 199 one of which is of circular and the other of rectangular cross section; the cross sectional area, however, could also be otherwise. The two threads 198 and 199 can be passed through corresponding holes in the fastener elements 104 which are secured in any convenient manner on the threads, for example by an adhesive, by pressing or soldering, or by die casting the elements on the threads, or by casting the threads and the fastener element in a single piece, in which case the threads 198 and 199 form webs between successive fastener elements. The connecting studs 108 are provided with a pointed end 109 and with an opening receiving a locking thread 112 after the ends of the studs have been stuck through the article 111.

As represented in Figs. 89 and 90 the fastener elements 104 are provided with a laterally open slot before they are fixed to the carrier 107. This latter is inserted into the slot and then an extension 201 originally provided on the fastener element is bent down upon the carrier which is thus firmly clamped in the slot. The connecting stud 202 is formed as extension of the fastener element and provided with a hook-shaped end 203 forming a retaining surface 204. In order to attach the stringer to a piece of cloth 111, the studs are stuck through the cloth and through a washer strip 185 of yielding material until the shoulder 205 of the stud abuts against the outer surface of the cloth. The retaining surface 204 bearing against the washer strip 185 prevents the studs from being pulled off the cloth.

The fastener stringer represented in Figs. 91 to 93 is similar to the example just described. The flexible carrier 107 is inserted into a lateral slot in the fastener elements 104 and is clamped therein by means of two originally projecting noses 206 of the fastener elements. The end portion 203 of the connecting studs 202 is provided at opposite sides with two axially displaced retaining noses 207 and 208. The two noses are also laterally displaced as can be seen from Fig. 93 representing a cross section through a stud. In order to attach the stringer to a piece

of cloth 111 the end 203 of the stud is stuck with both retaining noses 207 and 208 through the cloth and through a washer strip 185 until the shoulder 205 of the stud abuts against the cloth. The upper retaining nose 207 then bears against the washer strip 185 and prevents the stringer from being pulled off the cloth 111.

In the example according to Figs. 94 to 96 the fastener elements 1 are provided with the coupling projection 2 and with the socket 3. At the end of the fastener element opposite to the coupling projection they are provided with a connecting stud 4 having two free end portions 50 and 51, which, as shown in Fig. 95, are spread apart before the fastener element is attached to a piece of cloth or other article 52. The two end portions 50 and 51 are provided on their sides facing each other with hooks 53 and 54. The fastener elements 1 are firmly secured to a carrier of wire, thread or band shape. The carrier 9 is again formed of a non-expansible but resiliently flexible material, as for example polyamide. The fastener elements 1 are directly die-cast on a carrier 9. They could also be secured to the carrier by pressure. The fastener elements can be made from metal or from thermoplastic material. For attaching a fastener stringer to an article 52, the edge of the article is introduced between the spread apart end portions 50 and 51 of the connecting studs as shown in Fig. 95 and then both end portions are pressed towards each other by means of any suitable instrument, so that the hooks 53 and 54 penetrate into the material of the article 52 and produce a firm connection of the stringer with the article. The two hooks 53 and 54 of the end portions 50 and 51 are axially displaced so that they do not prevent each other from penetrating into the material. The width of the connecting stud 4 is smaller than that of the fastener element so that shoulders 6 are formed between the connecting stud and the fastener element for guiding the slider 7 of the fastener.

In the example according to Figs. 97 and 98 the carrier 9 is inserted into a groove 55 provided in the lower portion of the fastener element laterally of the connecting stud 4 and then the projection 56 on the fastener element is bent towards the carrier 9 and pressed against the latter so as to ensure a firm connection of the fastener element with the carrier. The attachment of the fastener elements on the article 52 which is to be provided with the fastener is effected in the same manner as in the example according to Figs. 94 to 96, by means of the end portions 50 and 51 of the connecting studs 4. Guiding of the slider is obtained by means of shoulder surfaces 6 on both sides of the connecting stud 4.

In the modification according to Figs. 99 and 100 a groove 55 is provided in the central portion of the fastener element, while the connecting stud 4 is disposed on one side of the element. The carrier thread 9 placed in the groove 55 is fixed to the fastener element 1 by clamping the projection 56 down on the carrier. A guiding surface 6 for the slider is disposed on one side of the fastener element. The connecting stud 4 is again provided with two free end portions 50 and 51 which are clamped towards each other for attaching the stringer formed by the fastener elements and the carrier 9 to the article 52, whereby the hooks 53 and 54 penetrate into the material of the article.

The fastener element shown in Fig. 101 is at-

tached to the carrier 9 by having the carrier inserted into a groove provided in the connecting stud 4 and fixed therein by pressing the material of the stud towards the carrier. The connecting stud is again provided with two free end portions 50 and 51 for attaching the fastener element to the article to be provided with the fastener.

In Fig. 102 the connecting stud is disposed laterally on the fastener element 1 and the carrier 9 is clamped in a groove of the connecting stud. A guiding surface 6 is provided on the fastener element for the operating slider of the fastener.

The modification shown in Fig. 103 is similar to that shown in Fig. 102 with the exception that the free end portions 50 and 51 of the connecting studs are each provided with two prongs or hooks 53 and 54.

In the example according to Figs. 104 and 105 the connecting stud 4 of the head portion 1 of the fastener element is provided with a laterally open groove 57 for the carrier thread 9. The connecting stud is provided on one side of the head portion 1, while on the other side of this portion a guide surface 6 for the slider is provided. Above and below the groove 57 the material of the connecting stud forms projecting noses 58 which are pressed upon the carrier 9 after this latter is placed in the groove, so as to firmly lock the fastener element on the carrier. For attaching the fastener element to an article 52 the connecting stud 4 is provided with two free end portions 50 and 51 which are clamped together after the edge portion of the article has been inserted between them.

In the example according to Figs. 106, 107 and 108 the carrier 9 of the fastener elements is secured in a groove in the head portion of the element, laterally of the connecting stud 4. This latter is provided with two free end portions 59 and 60 having pointed ends 61 and 62 which are displaced relatively to each other in the plane of the stringer. For attaching the stringer on an article the edge portion of this latter is introduced between the end portions 59 and 60 which are then clamped towards each other so that the pointed ends 61 and 62 traverse the material of the article.

The fastener element represented in Figs. 109 and 110 is provided with a groove 57 in the connecting stud 4 for insertion of the carrier thread 9 which is clamped in the groove by pressing the two projections 58 of the material of the connecting stud against the carrier. The stud 4 is provided with two end portions 63 and 64 which are spread apart before the fastener element is attached to an article. The end portion 63 is provided with small prongs 65, and the end portion 64 with corresponding conical holes 66. For attaching the fastener element to the article, an edge portion of this latter is introduced between the two end portions 63 and 64 which are then pressed together so that the prongs 65 penetrate through the material of the article and into the holes 66 of the end portion 64, where they are then riveted as shown in Fig. 110.

In the example according to Figs. 111 and 112 the carrier 9 is secured in a groove 57 of the fastener element by pressing the projections 58 over the carrier inserted in the groove. The connecting stud is provided with two free end portions 67 and 68, of which the portion 67 has a hook-shaped pointed end 69, while the portion 68 is provided with a recess 70. In order to at-

tach the fastener element to an article 52 an edge portion of the article is introduced between the spread apart end portions 67 and 68 and then these latter are clamped towards each other, so that the hook-shaped end 69 penetrates through the material of the article 52 and into the recess 70 of the portion 68, to engage behind the nose 71 of this portion. Afterwards the end 72 of the portion 68 is pressed upwardly towards the hook-shaped end 69 so that this latter is maintained in engagement with the nose 71. In the examples according to Figs. 109 to 112, it is not necessary that both end portions of the connecting studs are spread apart before introducing an edge portion of the article to be provided with the fastener between the two end portions. One of the end portions 63 and 64, or 67 and 68 could originally extend parallelly with the vertical axis through the fastener element, and after placing this end portion on the edge of the article, the other end portion can be closed upon the first one.

In the modification according to Figs. 113 and 114 the fastener element is secured to a carrier 9 inserted into a groove provided in the element. The connecting stud 4 is provided with two free end portions 73 and 74. The end portion 73 forms an extension of the connecting stud 4 and is directed according to the vertical axis of the fastener element 1, while the end portion 74 is spread laterally.

Both end portions are provided with hook-shaped ends 75. For attaching the fastener element to an article such as a piece of cloth 52 the end portion 73 is stuck through the edge portion of the cloth and this edge portion is then folded down and sewn to form a seam as shown in Fig. 114. The hooks 75 of the portion 73 now prevent the stud from being pulled off the article 52. The end portion 74 is then closed down towards the portion 73 so that a portion of the seam of the cloth is clamped between the two end portions of the connecting stud.

The fastener element shown in Figs. 115 and 116 is provided with a connecting stud 4 having three end portions 73, 74 and 74'. For attaching this fastener element to a piece of cloth or other material 52 the central portion 73 is stuck through the cloth and the edge portion of the cloth is folded down to form a seam. The two

lateral end portions 74 and 74' are then bent towards the central portion 73, so that both branches of the seam are clamped between two end portions of the connecting stud 4.

While I have shown and described a number of embodiments which my invention may assume in practice, it will be understood that variations may be made in the configuration and combination of the several parts without departing from the spirit of the invention or the scope of the appended claims.

I claim:

1. A stringer forming one complementary part of a multiple operated fastener, said stringer comprising a row of fastener elements each having a head portion formed with interlocking means thereon, each fastener element having an elongated rigid stud extending from the head portion, each stud being pointed to provide fabric penetrating means, the stud also having fabric engaging and retaining means to prevent withdrawal after penetrating a fabric, said row of fastener elements being supported upon a carrier member which is resiliently bendable but substantially non-extensible.

2. A stringer according to claim 1 in which the carrier member extends through each of said fastener elements at a point located between the interlocking means and the stud.

3. A stringer according to claim 1 in which each of the fastener elements has a slider guide surface extending in a plane at right angles to the plane of said stud.

4. A stringer according to claim 1 in which the retaining means comprises a shouldered surface spaced inwardly from the pointed end on said stud.

5. A stringer according to claim 1 in which the carrier member is of wire-like construction and relatively small in transverse cross section when compared with the transverse dimensions of the fastener element.

6. A stringer according to claim 1 in which the carrier member extends through a notch in the fastener element head, said fastener element being clamped to said carrier member whereby each fastener is maintained in a fixed position on the carrier element.

MARTIN WINTERHALTER.
